UNITED STATES PATENT OFFICE.

EDWARD F. MALOUF, OF MARYSVILLE, CALIFORNIA.

NAIL SETTER.

Application filed February 12, 1927. Serial No. 167,744.

My invention relates to nail setters adapted for setting nails at predetermined spots, and it appertains particularly to nail setters adapted for the use of workmen, such as shoemakers, cobblers, shinglers, carpet and linoleum layers, or others, who are required to set a quantity of nails or tacks of the same kind.

The main object of the invention is to provide a nail setter, which is adapted to receive a number of nails therein and to be moved to a nail-setting position and held and manipulated by one hand of an operator so as to cause the nails to be conveyed one at a time to the setting position, while the operator's other hand is free to set the nails with a hammer. The invention thus substitutes a safe method of nail-setting for the prevailing practice among workmen to take a number of nails in the mouth, a practice often resulting in injury to the teeth of the workman and causing the workman to swallow some of the nails so that his health is thereby jeopardized.

Another important object of the invention is to provide manually operated means for releasably holding a nail in the nail setter in order that, when the nail is placed in the setting position on an object, the operator, by exerting the required amount of pressure upon the nail and by contacting the point of the nail with the surface of the object, may slide the nail so that the head thereof is pushed out of contact with the nail setter and therefore the nail can be hit with a hammer without liability to injury of the nail setter.

A further object is to provide a nail setter with means for yieldingly retaining the nails therein, so that, when the nails are released from the means for holding them in the position for setting, they may also be easily freed from the nail setter without causing injury to the latter.

A still further object is to provide a nail setter with means for adjusting it so as to accommodate nails or tacks of different thickness.

Another feature of the invention is to provide a nail setter with a guide member adapted to engage the edge of an object so that the nail setter may be moved along the edge for setting nails at predetermined spots on the object.

Still further objects and features will appear from the following detailed description,

having reference to the accompanying drawings, in which a preferred embodiment of the invention is illustrated and in which:

Figure 1 is a side elevation of the nail 60 setter, with the operating parts thereof in their normal position;

Figure 2 is a plan of the nail setter, with the operating parts in the positions shown in Figure 1, and with the guide member in engagement with the edge of a shoe sole, which is indicated by a dot-and-dash line, while the predetermined spots, at which the nails in the nail setter may be set, are indicated by a dotted line;

Figure 3 is a plan of the nail setter, with a portion of the nail conveyer in section in order to show clearly the bars that operate so as to allow only one nail at a time to pass through the conveyer, the bar nearest to the 75 nail receptacle having been moved by the sliding movement of the receptacle so that it retains the nails in the conveyer, while the other bar at the same time has been moved so as to allow one nail to pass to the 80 free end of the conveyer, where it is held by the nail-holding member, preparatory to the setting of the nail;

Figure 4 is a side elevation of a portion 85 of the plate, upon which the nail receptacle and the nail conveyer are supported, and the free end portion of the nail conveyer, with the element for releasably holding a nail therein, and also the means, by which the element is manually operated, and the connections of the manually operated means 90 with the supporting plate and the nail conveyer, the operating parts being in their position for holding a nail in the nail conveyer;

Figure 5 is an enlarged plan of the free 95 end portion of the nail conveyer and shows the spring for retaining the nails at the end of the conveyer, the rocking element in the conveyer, and also parts of the manually 100 operated means for actuating the rocking element, which is shown in its nail-holding position, a portion of the conveyer member, in which the rocking element is mounted, and the pivot for the rocking element, as 105 well as the nail held thereby, being taken sectionally above the rocking element in order to disclose clearly the operation of the element;

Figure 6 is a somewhat diagrammatic 110 side elevation of the nail setter having attached thereto a specially formed guide

member, which is particularly adapted for the use of shinglers, the guide member being shown as applied to three layers of shingles which are indicated by dot-and-dash lines; 5 and

Figure 7 is a sectional view taken along the line 7—7 in Figure 3, the view showing the screw with the taper end for adjustably separating the bars in the nail conveyer, 10 and the spring that urges the bars into a yielding contact with the taper end.

In the drawings the complete nail setter of my invention is indicated by the numeral 1. This nail setter comprises a frame 2, 15 which includes a main handle 3 fixed to one end of the frame by any suitable means. In the preferred form of the invention the frame has at its other end a guide member 4, which is provided with a stem 5 adapted 20 to be threaded into the frame so as to be adjustably secured thereto. By this arrangement an operator may take hold of the handle and, after placing the frame upon an object so that the guide member contacts 25 one edge of the object, may thereby move the nail setter along the edge, which in Figure 2 is indicated by a dot-and-dash line as being the edge of a shoe sole, for setting nails at predetermined spots on the sole, as indicated by a dotted line in the same figure.

The handle 3 is preferably hollow and has adjustably secured therein the shank of a mounting member 6 by screws 7, and to the head of this mounting member is fixed a bar 35 8, which extends with its major portion in the general direction of the frame 2. Upon the mounting member 6 are also fixed guide plates 9 and 10, each of which is provided with an opening 11 for slidably receiving a 40 rod 12 therein, and other plates 13 and 14 are respectively attached to the guide plates 9 and 10 for retaining the rod 12 in the openings 11 of the guide plates. Outside of the 45 plate 10 the rod 12 is connected with one end of an auxiliary handle 15, which has its other end attached to another rod 16 slidably extending through the main handle 3 in a substantially parallel relation to the rod 12, and springs 17 and 18 are coiled around the 50 respective rods 12 and 16, a pin 19 being provided for engaging one end of the spring 17, and a pin 20 being similarly provided for engaging one end of the spring 18, while the springs with their other ends respectively contact the plate 10 and the handle 3.

The nail setter 1 further comprises a nail receptacle 21 consisting of wall portions 22 and 23 and having the portion 22 provided with wall additions 24, which converge toward the bottom of the receptacle, and the 55 side portions of the receptacle are preferably correspondingly inclined toward the bottom of the receptacle. A nail conveyor 25 consisting of a pair of suitably formed members 26 and 27 adapted to extend along

side of, and to be spaced from, each other, have the members 26 and 27 respectively connected with the wall portions 22 and 23 of the nail receptacle.

For adjustably attaching the conveyor 70 member 26 and 27 to each other, blocks 28, arranged in pairs, may be secured to the members by any suitable means, such as screws 29, and a plate 30, having slots 31 therein, is provided, so that the nail receptacle 21 and the nail conveyor 25 may thereby be mounted on the plate with a certain degree of adjustability and firmly secured to the plate by the respective screws 29. In each pair of the blocks 28 one of the blocks 75 preferably has a dowel 32 fixed therein, while the other block has a corresponding hole for slidably fitting the block on the dowel. Also, a screw 33 is shown as being threaded through one block in each pair, while the other block in the pair is drilled for clearance of the screw, and around the screw and between the two blocks in each pair is placed an expansion coil spring 34. 80 Thus, by the turning of the screws 33 and by the co-operating action of the springs 34, the conveyer members 26 and 27 are adapted to hold a row of nails therebetween, and they may be spaced from each other so as to accommodate therebetween nails of different 85 thickness. It should also be observed that the wall portions 22 and 23 of the nail receptacle, by their attachment to the respective conveyer members, are adjustable therewith and adapted to form a longitudinal opening 90 at the bottom of the nail receptacle in registration with the space between the conveyer members in order to accommodate the heads of the nails held in the nail conveyer.

Each of the conveyer members 26 and 27 is 95 preferably curved, as viewed laterally and as shown in Figure 1, and a plate 35, extending over the conveyer members and corresponding in curvature with them, is secured to one of the members so as to be spaced 100 from them sufficiently for allowing a free sliding of the nail heads between the plate and the conveyer members, while at the same time the plate prevents an upward discharge of the nails from the nail conveyer. 105 To the plate 30 is secured an angle plate 36 at one of its wings, and at its other wing the bracket is secured to the rod 12. The bracket thus supports the nail receptacle 21 and the nail conveyer 25 in inclined positions, so that nails or tacks 37, dropped into the receptacle and held between the conveyer members, as shown in Figure 3, may be moved by gravity toward the free end of the nail conveyer.

Near to the free end of the nail conveyer the conveyer member 27, preferably bifurcated for this purpose, has pivotally secured therein a rocking, nail-holding element 38, which is provided with a tongue 110

- 39 adapted to be engaged by a wedge-shaped portion 40 of a member 41 slidably retained upon the conveyer member by a bracket 42, and a spring 43 is suitably mounted for normally holding the element in a position so as to allow the nails 37 to pass to the free end of the nail conveyer, the sliding member 41 preferably being retractile only far enough from the rocking element to allow the proper operation thereof. In order to manually operate the rocking element for holding a nail at the free end of the nail conveyer the sliding member 41 is at its end opposite to the wedge portion 40 pivotally connected with one arm of a bell-crank lever 44, and the other arm of the bell-crank lever is in its turn pivotally connected with one end of a rod 45, slidably mounted in brackets 46 on the plate 30 so as to be inclined toward the bell-crank lever and in a position for the free swinging thereof, the pivotal connections of the bell-crank lever 44 with the sliding member 41 and the rod 45, of course, being such as to allow a free swinging movement of the lever. At its upper end the rod 45 is preferably provided with a button 47, and a compression spring 48, which is coiled around the rod between the uppermost bracket 46 and a collar 49, secured to the rod, serves to hold the rod pushed upward so as to allow the rocking element 38 to be swung to, and normally retained in, its nail-clearing position in the nail conveyer.

50 A spring 50 is secured to the conveyer member 26 at a short distance from the free end of the nail conveyer. This spring is bent so as to extend transversely of the nail conveyer at its free end, as shown in Figures 2, 3 and 5, so that, when a nail has passed through the nail conveyer to its free end, the spring yieldingly retains the nail thereto, and the rocking element 38 may be provided with a cut-out portion 51, and it is otherwise so shaped that by a sufficient rocking movement against the tension of the spring 43 the element is adapted to catch the nail at the free end of the nail conveyer in the portion 51, and that therefore, when the nail is thus pressed against the conveyer member 26, it is held frictionally in the nail conveyer.

51 Preferably at the beginning of the curved portion of the nail conveyer the conveyer member 27 has secured thereto a bracket 52, which extends toward the bar 8 and has oscillatively secured thereupon a member 53 provided with an arm 54, which is adapted to be engaged by tripper bars 55 adjustably secured upon the bar 8. Upon the oscillative member 53 and on each side of the pivot therefor is pivotally attached a block 56, and each block 56 has secured thereto one end of a bar 57. These bars 57 extend alongside of each other and transversely of

52 the nail conveyer 25 and are adapted by the oscillative movement of the member 53 to slide alternately across the space between the conveyer members 26 and 27, so that, when the nail conveyer is in its normal position, as shown in Figure 2, a row of nails 37 is retained in the conveyer by one bar, and, when the nail conveyer is moved from its normal position to the position shown in Figure 3, this bar is retracted and thereby releases the nail nearest thereto so as to allow the nail to move by gravity toward the free end of the conveyer. Into the bracket 52 is threaded a screw 58, which has a taper end adapted to extend between the bars 57, and the conveyer member 27 has therein a cut-out portion 59, in which extends a spring 60 suitably secured to the bracket 52 and provided with arms terminating in portions that hook over the respective bars 57. This spring is tensioned so as to draw the bars normally toward each other. The screw 58, acting against the tension of the spring 60, thus serves as a means for adjustably separating the bars 57 in correspondence with the thickness of the nails that pass through the nail conveyer.

53 Before beginning the operation of the nail setter 1 the operator adjusts the nail receptacle and the nail conveyer for the required thickness of nails and places a quantity of the nails 37 in the nail receptacle. On account of the convergent side walls of the receptacle the nails will be disposed to form a single row at the bottom of the receptacle and between the members 26 and 27 of the nail conveyer, the heads of the nails preventing the nails from falling through the conveyer. The operator then grips the main handle 3 with the fingers of one hand, at the same time engaging the auxiliary handle 15 with the inside of the hand, and, placing the nail setter in its desired position on an object, contracts the hand and thereby moves the auxiliary handle toward the main handle against the tension of the springs 17 and 18. This motion causes the nail receptacle and the nail conveyer to move forward and the arm 54 of the oscillative member 53 to contact the forward tripper bar 55 and to be moved thereby, thus retracting the forward bar 57 and allowing the nail 37 nearest thereto to pass to the free end of the nail conveyer, where it is retained by the spring 50. With the thumb of the same hand that holds the handles 3 and 15 the operator then depresses the button 47 and thus causes the rod 45 to rock the element 38 to its position for catching and holding the nail in, and at the free end of, the conveyer. The nail may then be held with any required tension in the conveyer, according to the amount of pressure the operator exerts upon the button 47.

For some nail-setting work the use of the guide member 4 is not required, and in such cases it may be removed from the frame 2. However, it may expedite the nail setting 5 to use the guide member, for instance, in connection with work on shoe soles, as indicated in Figure 2, and on other objects or whenever it is convenient to guide the nail setter along the edge of an object for setting 10 nails at predetermined spots thereon.

In order to adapt the nail setter particularly for the use of shinglers the main handle 3 may be supported upon a specially formed guide member or frame structure 61, 15 which is formed with end portions 62 and 63, preferably at substantially right angles to the intermediate part of the frame structure, as shown in Figure 6, in which shingles are indicated by dot-and-dash lines. In 20 this form of the nail setter the auxiliary handle 64 may extend into the frame structure 61 so as to be adapted to slide with its lower end in a slot formed longitudinally in the frame structure. The end portion 25 62 is shorter than the end portion 63 so that the inside of the end portion 63 may be placed along the end edge of a shingle in one row, and a shingle in a succeeding row may be placed in the desired nailing position 30 with its end edge in contact with the outside of the end portion 62, the distance between the inside of the end portion 63 and the outside of the end portion 62 thus determining how much of the shingle surfaces is to be 35 exposed to the weather.

Although in the foregoing I have described one embodiment of my invention, it is evident that the principle thereof can be embodied in other forms. I therefore reserve 40 the right to make such modifications and changes as are in accordance with the spirit of the invention and come within the scope of the appended claims.

I claim:

45 1. In a nail setter adapted for setting nails at predetermined spots, a frame; a receptacle slidably mounted on the frame and adapted to receive nails therein; conveying means connected with the receptacle for leading nails therefrom; and manually operated means for holding a nail in the conveying means while the nail is set.

50 2. In a nail setter adapted for setting nails at predetermined spots, a frame; a receptacle slidably mounted on the frame and adapted to receive nails therein; a nail conveyer connected with the receptacle for leading the nails therefrom; means for allowing the passage of only one nail at a time 55 through the nail conveyer to the free end thereof; means at the free end of the nail conveyer for yieldingly retaining the nail passed through the conveyer; and manually operated means for holding the nail in, and

at the free end of, the nail conveyer while 65 the nail is set.

3. In a nail setter adapted for setting nails at predetermined spots, a frame; a nail conveyer comprising a pair of members slidably connected with the frame and adapted 70 to be spaced from each other so as to hold a row of nails between them; means for spacing the conveyer members from each other so as to accommodate nails of different thickness in the conveyer; a nail receptacle comprising wall portions connected with the respective conveyer member so as to be adjustable therewith and adapted to form a longitudinal opening at the bottom of the receptacle in registration with the space between the conveyer members in order to accommodate the heads of the nails in the row between the conveyer members; means at the free end of the nail conveyer for yieldingly retaining the nails passed through the conveyer; and manually operated means for holding the nail in, and at the free end of, the conveyer while the nail is set.

4. In a nail setter adapted for setting nails at predetermined spots, a frame; a nail conveyor comprising a pair of members slidably connected with the frame and adapted to be spaced from each other so as to hold a row of nails between them; means for spacing the conveyer members from each other so as to accommodate nails of different thickness in the conveyer; a nail receptacle comprising wall portions connected with the respective conveyer members so as to be adjustable therewith and adapted to form a longitudinal opening at the bottom of the receptacle in registration with the space between the conveyer members in order to accommodate the heads of the nails in the row between the conveyer members, the nail receptacle and the nail conveyer being adapted to be held in an inclined position so that the nails may be moved by gravity toward the free end of the conveyer; a member oscillatively mounted on the conveyer; bars pivotally connected with the oscillative member and slidably mounted alongside of each other so as to extend transversely of the conveyer, the bars being adapted to slide alternately across the space between the conveyer means, so that, when the nail conveyer is in its normal position, the nails are retained in the conveyer by one bar, and when the nail conveyer is moved from its normal position this bar is retracted and thereby releases the nail nearest thereto so as to allow the nail to move toward the free end of the conveyer while the second bar retains the other nails in the conveyer; means secured to the frame for operating the oscillative member when the nail conveyer is slid; means at the free end of the nail conveyer for yieldingly retaining the nail passed

through the conveyer, and manually operated means for holding the nail in, and at the free end of, the nail conveyer while the nail is set.

5. In a nail setter adapted for setting nails at predetermined spots, a frame, a nail conveyer comprising a pair of members slidably connected with the frame and adapted to be spaced from each other so as to hold a row 10 of nails between them; means for spacing the conveyer members from each other so as to accommodate nails of different thickness in the conveyer; a nail receptacle comprising wall portions connected with the respective conveyer members so as to be adjustable therewith and adapted to form a longitudinal opening at the bottom of the receptacle in registration with the space between the conveyer members in order to accommodate 15 the heads of the nails in the row between the conveyer members, the nail receptacle and the nail conveyer being adapted to be held in an inclined position so that the nails may be moved by gravity toward the 20 free end of the conveyer; a member oscillatively mounted on the conveyer; bars pivotally connected with the oscillative member and slidably mounted alongside of each other so as to extend transversely of the conveyer, the bars being adapted to slide alternately across the space between the conveyer members, so that when the nail conveyer is 25 in its normal position, the nails are retained in the conveyer by one bar, and, when the nail conveyer is moved from its normal position, this bar is retracted and thereby releases the nail nearest thereto so as to allow the nail to move toward the free end of the conveyer while the second bar retains the 30 other nails in the conveyer; means secured to the frame for operating the oscillative member when the nail conveyer is slid; means for adjustably separating the bars in correspondence with the thickness of the nails 35 that pass through the nail conveyer; means at the free end of the nail conveyer for yieldingly retaining the nail passed through the conveyer; and manually operated means for holding the nail in, and at the free end 40 of, the nail conveyer while the nail is set.
6. In a nail setter adapted for setting nails at predetermined spots, a frame; a receptacle slidably mounted on the frame and adapted to receive nails therein; a nail 45 conveyer connected with the receptacle for leading the nails therefrom; spring means at the free end of the nail conveyer for yieldingly retaining the nails passed through the conveyer; and a rocking element pivotally secured to the nail conveyer and adapt-

ed to be manually operated for holding a nail at the free end of the nail conveyer while the nail is set.

7. In a nail setter adapted for setting nails at predetermined spots, a frame; a receptacle slidably mounted on the frame and adapted to receive nails therein; a nail conveyer connected with the receptacle for leading the nails therefrom; means at the free end of the nail conveyer for yieldingly retaining the nails passed through the conveyer; a rocking element pivotally secured to the nail conveyer and adapted to be swung so as to hold a nail in, and at the free end of, the nail conveyer; means for normally urging the rocking element away from its nail-holding position; and means associated with the nail conveyer and adapted to be manually operated for swinging the rocking element to, and retaining 70 the element in, the nail-holding position; and means adapted to hold the manually operated means normally in a position for allowing the rocking element to be swung away from its nail-holding position. 75

8. In a nail setter, a frame; a receptacle slidably mounted on the frame and adapted to receive nails therein; conveying means connected with the receptacle for leading the nails therefrom; a guide member secured to the frame and adapted to engage the edge of an object so that the nail setter may be moved along the edge for setting nails at predetermined spots on the object; and manually operated means for holding 80 a nail in the conveying means while the nail is set on the object. 85

9. In a nail setter, a frame formed with a main handle whereby the nail setter is adapted to be moved manually for setting 90 nails at predetermined spots on an object; an auxiliary handle slidably connected with the main handle and the frame and adapted to be grasped together with the main handle by the hand of an operator and to be pressed 95 thereby toward the main handle; means for normally urging the auxiliary handle away from the main handle; a receptacle adjustably connected with the auxiliary handle and adapted to receive nails therein; a nail 100 conveyer connected with the receptacle for leading the nails therefrom; means operable by the movement of the auxiliary handle to and from the main handle for allowing the nails to pass one at a time from the receptacle to the free end of the nail conveyer; and manually operated means for holding 105 a nail in, and at the free end of, the nail conveyer while the nail is set on the object. 110

EDWARD F. MALOUF.
